UNITED STATES PATENT OFFICE

ALBERT L. BLATTI, OF CHICAGO, ILLINOIS

DISPENSING DEVICE

Application filed March 5, 1928. Serial No. 259,130.

This invention relates to article dispensers and more particularly to cigarette dispensing devices, although certain features thereof may be employed with equal advantage for other purposes.

It contemplates more especially the provision of means for dispensing delicate articles such as cigarettes which are subject to destruction responsive to the application 10 of any instrumentalities which create a stress thereon incident to the mechanical handling thereof. As a consequence, it is necessary or at least highly desirable to handle such articles without crushing or applying any instrumentalities thereto to effect the 15 selective dispensation thereof.

One object of the present invention is to simplify the construction and improve the 20 operation of devices of the character mentioned.

Another object is the provision of means for selectively dispensing articles without necessitating the application of instrumentalities thereto.

Still another object is to provide means for selectively discharging articles along a predetermined path without necessitating the gripping thereof.

A further object is to provide means for feeding articles along a predetermined path in conjunction with simultaneously operable ejecting means which coordinates therewith.

A still further object is to provide article supporting means adjustable to coordinate 35 with an ejector for simultaneous operation to effect the discharge of articles.

Other objects and advantages will appear from the following description of an illustrated embodiment of the present invention.

In the drawing:

Figure 1 is a sectional view in elevation of a device embodying features of the present invention.

Figure 2 is a similar view showing parts 45 thereof removed and the exterior construction thereof.

Figure 3 is an end view in elevation of the device disclosed in Figure 1.

Figure 4 is a plan view of the device dis- 50 closed in Figure 2.

Figure 5 is a sectional view taken substantially along line V—V of Figure 2.

The structure selected for illustration comprises a base member 10 stamped or otherwise shaped to provide a hollow interior for the purpose of receiving and concealing the operating instrumentalities from view. A substantially rectangular body member 11 is associated with the base 10 with the forward wall 12 thereof disposed rearwardly of the front edge of the base 10. A partition member 13 is disposed within the body 11 to extend between the sides thereof for defining independent compartments 14 and 15 constituting the article confining magazine and ash chamber, respectively.

As shown, the forward wall 12 extends downwardly for termination in an inclined wall 16 which cooperates with a flange 17 formed from a forward portion of the base 10. The flange 17 is spaced from the terminal edge 16' of the inclined wall 16 to define a substantially rectangular, transversely disposed opening 18 which corresponds in size and contour to the articles, in this instance cigarettes 19. The articles or cigarettes 19 are supported in stacked relation within the magazine 14 by means of a tray 20 which is pivoted to the partition 13 by means of a hinge 21 having a pin 22 projecting therethrough. The free extremity 23 of the tray 20 is disposed in the path of a plate 24 of curved contour conforming substantially with the wall 16 in spaced relation thereto so as to form a chute 25 slightly greater in width than the cigarettes 19 which are freely movable therethrough.

It is to be noted that the chute 25 communicates with the magazine 14 to receive cigarettes 19 from the tray 20 which is slightly inclined in its extreme counterclockwise position. In order to guide the articles 19 through the chute 25, a plate 26 is associated with the wall 16 to conform substantially with the curvature of the plate 24, thereby serving as a smooth guideway for the cigarettes which tend to normally gravitate to the opening or discharge orifice 18 supra. As a result, the tray or support 20 100

constituting the bottom of the magazine 14 will tend to supply and maintain the chute 25 filled with articles which are selectively ejected through the orifice 18.

6 The ejector means consist of a transversely disposed member, in this instance a U-shaped plate 27 which is mounted near the extremity of a bar 28 for reciprocal movement in the path of the chute 25 to normally 10 serve as a closure therefor. To this end, the bar 28 is pivotally associated to a depending lug 29 struck from the base member 10 or otherwise associated therewith to depend therefrom, thereby enabling a pin 15 30 to project therethrough to sustain and pivotally support the bar 28 which is concealed within the interior of the base 10. The ejector 27 will reciprocate in a substantially vertical direction responsive to im- 20 parting pivotal movement to the support bar 28 by means of a manually operative actuator 31 having the shank 32 thereof secured thereto at the extremity 33 thereof. It is to be noted, that the actuator shank 25 32 projects through the aperture 34 provided in the base 10 to enable access to the actuator 31 from the exterior of the body 11.

The ejector 27 comprises a transversely disposed inverted U-shaped blank of a depth 30 somewhat greater than the chute 25, it being normally maintained in the path thereof by means of a tension spring 35 which is secured to a tank 36 struck from the partition 13. The other extremity of the spring 35 is secured to the bar 28 intermediate the ends thereof to maintain the bar 28 with the ejector 27 in an extreme upward position. The upward movement of the ejector 27 is limited by means of a stop 37 secured 40 thereto so as to engage the floor of the base 14 at the juncture thereof with the plate 24 which constitutes a wall of the chute 25.

The ejector 27 is provided with a substantially arcuate depression 38 in the top surface thereof to receive an article, in this instance a cigarette 19, thereon responsive to the downward movement of the ejector 27 by manipulating the actuator 31, thereby placing the depression 38 substantially in extensive alignment with the plate 24 of the chute 25. The cigarette 19 most proximate to the orifice 18 will gravitate thereon for retention with the depression 38 (Figure 1). It will thus be apparent that the deposition 50 of the article 19 within the depression 38 will retain the other articles within the chute in such a position as to preclude the discharge thereof. Simultaneous with the removal of the applied force from the actuator 31, the tension spring 35 elevates the ejector 37 to a position in the path of the chute 25, thereby eliminating any further possible passage of articles therethrough and delivering the ejected cigarette to a ready 65 accessible position.

The chute 25 is maintained filled with articles supplied from the magazine 14, and the last article is capable of ejection therefrom by means of the movable tray 20 which serves as a support for the articles within the magazine 14. It has been found desirable to return the tray 20 to its normal supporting position so as to preclude the delivery or gravitation of articles 19 to the chute 25 in order to relieve the articles in the chute 25 from the pressure or weight of the superposed articles within the magazine 14. To this end, the ejector supporting bar 28 is provided with an extension 39 which projects through an aperture 40 in the floor of the base 10 to normally abut against the tray 20 which assumes a substantially horizontal position simultaneous with the elevation of the ejector 27 in the path of the chute 25. In order to limit the clockwise movement of the tray 20, a flange 41 is secured to the under side thereof so as to project in the path of the wall 24 of the chute 25 to engage therewith. The oscillatory movement of the tray 20 is thereby limited between predetermined points to insure the proper operation of the instrumentalities and the desired gravitation of the articles 19.

The ash and refuse compartment 15 is provided with a drawer 42 disposed near the bottom thereof to serve as a receptacle to receive the refuse. The drawer 42 is movable horizontally for withdrawal from the chamber 15 by exerting a pull on the knob 43 secured to a wall thereof and accessible from the exterior. This arrangement permits cleansing of the receptacle 42 and the removal of the refuse therefrom with utmost convenience. The compartment 15 is provided with the cap 44 stamped or otherwise shaped to provide a depression 45 which is provided with a polygonal opening 46 therein to enable the passage of refuse therethrough and the deposition thereof within the receptacle 42 disposed therebelow. As shown, the marginal edge of the cap 44 which telescopically engages the mouth of the refuse compartment 15, is provided with opposed arcuate clips 47 to sustain cigarettes or other articles thereon. A closure 48 is pivoted to an edge of the cap 44 proximate to the partition 14 so as to effect the disposal thereof in the vicinity of the article magazine 14 to serve as a closure therefor, thereby precluding the entrance of dust and other foreign substances therein.

A resilient plate 49 is vertically associated with a member 50 secured to the forward inclined wall 16 of the body 11 so as to enable the reception of a match box between the forward wall 12 of the magazine 14 and the plate 49. A metallic member 51 is disposed between the plate 49 and the magazine 14 to support the match receptacle in the 125 130

proper position so that the slidable enclosure thereon can protrude downward beyond the sides of its match receptacle to enable access to the matches in the usual manner.

5 With the arrangement of parts above described it will be apparent that novel means have been provided to eject articles without injury thereto or in any way defacing such as to render them unfit for their intended purpose. The gravitation of articles from the magazine to the chute responsive to the selective ejection thereof precludes clogging as well as excessive weight thereon which often results in injury thereto owing to the 15 fact that the contents of the cigarette are not totally enclosed at the ends.

Various changes may be made in the embodiment of the invention herein specifically described without departing from or sacrificing any of the advantages thereof as defined in the appended claims.

I claim:

1. In a device of the character described, the combination with a magazine for confining articles in stacked relation, there being a discharge opening at one side thereof for normally delivering the articles from said magazine, means reciprocable in the path of said opening and pivotally mounted 25 at the other side of said magazine to control the ejection of articles therethrough, there being an article receiving depression on said ejecting means, and an actuator for moving said ejecting means so that said article receiving depression is in the path of said discharge opening to receive an article therein.

2. The combination with a magazine for confining articles therein, of a chute in communication with one side of said magazine to receive an aligned series of articles therefrom, a member mounted at the opposite side of said magazine and movable in the path of said chute to normally serve as a 40 closure therefor, and an actuator operatively connected to said ejector to effect the removal thereof from the path of said chute to receive an article therefrom, there being a seat in said ejector to receive an article 45 from said chute.

3. The combination with a magazine for confining articles therein, of a chute in communication with one side of said magazine to receive an aligned series of articles therefrom, a member mounted at the opposite side of said magazine and movable in the path of said chute to normally serve as a closure therefor, an actuator operatively 55 connected to said ejector to effect the removal thereof from the path of said chute to receive an article therefrom, there being a seat in said ejector to receive an article 60 from said chute, an article in said ejector 65 serving to block said chute, and means to

return said ejector in the path of said chute.

4. In a cigarette dispensing device, the combination with a magazine having an ash receptacle therein, cigarette ejecting means associated with said magazine, a cigarette support telescopically engaging said ash receptacle, and a member associated with said cigarette support to serve as a closure for said magazine. 70

5. In a cigarette dispensing device, the combination with a magazine having an ash receptacle therein, cigarette ejecting means associated with said magazine, a cigarette support telescopically engaging said ash receptacle, and a member pivotally associated with said cigarette support to serve as a closure for said magazine. 75 80
